UNITED STATES PATENT OFFICE.

LOTTIE G. ROSENBAUM, OF NEW ROCHELLE, NEW YORK.

GIRDLE.

Application filed June 29, 1923. Serial No. 648,429.

To all whom it may concern:

Be it known that I, LOTTIE G. ROSENBAUM, a citizen of the United States, residing at New Rochelle, in the county of West-
5 chester and State of New York, have invented certain new and useful Improvements in Girdles, of which the following is a full, clear, and exact description.

This invention relates to elastic girdles
10 which are commonly worn by women in place of corsets. In such girdles stiffening strips or stays are ordinarily provided at various points to prevent the elastic webbing from curling up and to give some support to the body. These strips extend substantially in a vertical direction above and below the waistline of the garment. In the region which covers the back of the wearer there are usually at least two of these stays
15 arranged normally approximately parallel and a slight distance apart. When the garment is applied to the body of the wearer, the horizontal tension upon the elastic web varies from a minimum at the waistline to a maximum at the upper and lower edges of the girdle. For this reason the two parallel stays, which are secured flatwise to the surface of the garment at the back, are separated from each other to various extents,
20 the upper and lower ends being drawn apart to a greater extent than the intermediate portions of the stays. Since these stays are flat and comparatively wide, they will not flex in the direction of their width and, consequently, to yield to the variable strains
25 of the garment, they are forced to twist, throwing their edges inward and outward instead of remaining flat as they are intended to do. This altering of the position
30 of the stays makes the garment uncomfortable to wear because the edges of the stays cut into the flesh of the wearer. Furthermore the edges which are presented outward cause unsightly ridges to appear on the outer garments, hasten the wear of the girdle and the outer garment and destroy the flat effect which the girdle is supposed to afford at the back.

An object of the invention is to provide
35 an improved elastic girdle, stiffened vertically in the section adapted to cover the back of the wearer, which will at all times be entirely comfortable to the wearer, which will not be subject to injury by excessive stretching of the stiffened section; in which the stiffening strips or stays will be effectively

prevented from twisting; and which will be simple and relatively inexpensive. Other objects and advantages will be apparent from the following description of an embodiment of the invention, and the novel features will be particularly pointed out hereinafter in claim.

In the accompanying drawing:

Fig. 1 is an elevation of a girdle constructed in accordance with the invention;

Fig. 2 is a sectional plan of a portion of the same taken substantially along the line 2-2 of Fig. 1;

Fig. 3 is an elevation of a slightly modified construction of a girdle embodying the principle of the invention;

Fig. 4 is a sectional plan of a portion of the same taken substantially along the line 4-4 of Fig. 3; and

Fig. 5 is an elevation of a portion of a further modified girdle, also embodying the principle of the invention;

Referring particularly to Figures 1 and 2, the girdle illustrated comprises a strip 1 of suitable elastic fabric having the usual covered and stiffened end sections 2 and 3 which are to be connected together when the girdle is applied to the body of the wearer. The section of the girdle which is adapted to cover the back of the wearer, is provided with a strip of inelastic fabric 4 such as coutil which is stitched along its edges thereto so as to create an inelastic zone in the portion covering the back of the wearer. The section of the girdle which is adapted to cover the back of the wearer, is provided with a strip of inelastic fabric 4 such as coutil which is stitched along its edges thereto so as to create an inelastic zone in the portion covering the back of the wearer. The fabric 4 and the strips 5 extend longitudinally of the girdle on both sides of the waist-encircling section 7, and may or may not extend entirely to the upper and lower edges of the girdle.

When a girdle constructed in this manner is applied to the body of the wearer, the edges 2 and 3 are connected together by the usual or any other suitable fastening devices 8, with the inelastic zone covering the back of the wearer. The strips or stays 5 flex inwardly and flatten off the back of the wearer so as to present a smooth surface

for the reception of the outer garments. The stretching of the girdle will be the least at the waist line and will increase in various extents above and below the waist line, 5 so that if the inelastic zone were not provided, the ends of the strips would be separated to a greater extent than the intermediate portions of the strips at the waist line. With the inelastic material stitched to 10 the elastic fabric so as to create the inelastic zone between or extending over the outer stiffening strips, the elastic fabric will stretch only in the sections on each side of the inelastic zone, and consequently the stiffening strips will flex normally and will not 15 be twisted by separation of the ends to greater extents than the intermediate portions. There will therefore be no tendency for the strips to present ridges bearing upon 20 the body of the wearer or showing as ridges through the outer garments of the wearer.

In the embodiment illustrated in Figures 3 and 4 the elastic band 9 forming the body of the girdle is similar to the band 1 of the 25 embodiment shown in Figures 1 and 2 and carries the usual or any suitable fastening means 8 by which the bound edges of the band may be secured together to encircle the body of the wearer. The stiffening strips 10 30 in the section adapted to cover the back of the wearer are each enclosed in a suitable covering 11 which is secured by stitching 12 to the elastic strip 9 so as to extend longitudinally of the girdle on opposite sides of the 35 waist-encircling section 13. A strip 14 of inelastic material such as coutil, is applied over the stiffening strips 10 and is secured by stitching 15 to the elastic band 9 on opposite sides of the portion stiffened by the 40 flexible strips 10.

When a girdle constructed as shown in Figures 3 and 4 is applied to the body of a wearer, the inelastic strip 14 which is secured to the elastic band 9 will prevent 45 stretching of the elastic fabric 9 beneath it, and will thus create an inelastic zone in the section adapted to cover the back of the wearer, in which the stiffening strips 10 are placed. Since the section of the elastic band

9 which is reinforced by the stiffening strips 50 cannot stretch, the stiffening strips cannot be twisted into an edgewise position by the unequal stretching of the fabric strip 9 on opposite sides of the waistline, and therefore the girdle will always fit smoothly and 55 comfortably across the back of the wearer. The continuous strip 14 which is stitched only at its edges, presents a neat appearance and conceals the stiffening strips.

In the embodiment shown in Figure 5, a 60 pair of stiffening strips 16 are secured in the usual manner to the elastic band 17 forming the body of the girdle, and the strips 16 extend in opposite directions beyond the waist encircling section 18. A strip 65 19 of inelastic fabric or other suitable material is secured to the elastic band 17 between the stiffening strips 16 by means of the stitching 20 which secures the strips 16 to the elastic band 17. The stiffening 70 strips 16 will thus be held against separation uniformly along the major portion of their edges and on opposite sides of the waist line, and consequently the section of the elastic band between the strips cannot 75 stretch. This effectively prevents twisting of the stiffening strips and causes the girdle to fit smoothly across the back of the wearer. This construction is exceedingly simple and inexpensive.

It will be obvious that various changes in the details and arrangements of parts herein described and illustrated for the purpose of explaining the nature of the invention, may be made by those skilled in the art 85 within the principle and scope of the invention as expressed in the appended claim.

I claim:

A girdle comprising a body encircling band the rear portion of which is elastic, said rear portion having a zone stiffened by vertical strips and an inelastic fabric substantially coextensive with said zone for preventing twisting of the strips during the stretching of the band.

In witness whereof, I hereunto subscribe my signature.

LOTTIE G. ROSENBAUM.
